Primary Examiner — Dominic V Simone(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the photographic area define the bounds of the claimed design and form no part thereof. The four unshaded broken line circles within the photographic area represent eyelets and form no part of the claimed design. The three straight broken lines within the photographic area represent slits that form no part of the claimed design. The broken lines depicting the remainder of the shoe show features that form no part of the claimed design.
